DESIGN FOR CARPET.

SPECIFICATION forming part of Design No. 24,622, dated August 20, 1895.

Application filed July 12, 1895. Serial No. 565,771. Term of patent 3½ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for Carpet or other Fabric, of which the following, taken in connection with the accompanying drawing, is a specification.

The design of my invention may be applied to or wrought in Brussels, Wilton, velvet, or other carpet and in such colors and combinations of colors as may be desired, and it is best described by means of illustration. Accordingly I declare that the drawing accompanying this specification presents to the eye of the observer a clear understanding of my new and original design, sufficient to enable such person to ascertain its leading characteristic or essential feature or features.

In the drawing, *a* is the body, *b* the border, and *a b* the carpet.

The leading or characteristic feature of my design may be said to be the ornaments *c*, displayed upon a background *d*, and in the drawing associated with bands *e*, *f*, *g*, and *h*.

What I claim as new, and desire to secure by Letters Patent, is—

1. In the design for carpet the body *a*, substantially as shown. 30
2. In a design for carpet the border *b*, substantially as shown.
3. The design for carpet consisting of the body *a*, and border *b*, substantially as shown.

In testimony whereof I have hereunto signed my name.

ARCHIBALD F. REDDIE.
